UNITED STATES PATENT OFFICE.

HERMAN F. RICHTER, OF LOS ANGELES, CALIFORNIA.

HYDROCARBON-BURNER.

1,293,198.

Specification of Letters Patent.

Patented Feb. 4, 1919.

Application filed December 31, 1917. Serial No. 209,754.

To all whom it may concern:

Be it known that I, HERMAN F. RICHTER, a citizen of the United States, residing at Los Angeles, in the county of Los Angeles and State of California, have invented a new and useful Hydrocarbon-Burner, of which the following is a specification.

My invention relates to burners for liquid fuels and has for its main object to completely vaporize and burn oils without a continuously burning heater.

Another object is to heat and vaporize the fuel when the burner is burning low as well as when a bright flame and intense heat is produced by the burner.

Another object is to provide a retort leading to the burner which can be moved into a position in relation to the burner to assure the right heating for fuel passing through the retort to the burner.

Another object is to provide a burner which can easily be cleaned while in operation by a suitable orifice cleaner disposed near the orifice of such burner.

Another object is to provide a burner which will resist the oxidizing process usually occurring in such hydrocarbon burners.

Other objects will appear from the following description and appended claims as well as from the accompanying drawing, in which—

Figure 1 is an end elevation of the device.

Fig. 2 is a detail grate member in end elevation.

Fig. 3 is a horizontal sectional view on line 3—3 of Fig. 1.

Fig. 4 is a fragmentary sectional view of the grate member having a non-oxodizing insertion.

Similar numbers refer to similar parts throughout the several views.

In Fig. 3, 5 designates the front-end plate, 6 the rear-end plate, 7 the several grate or body members, and 8 the bolts by which the whole is held together. The front-end plate is provided with a sleeve extension 9 into which the burner is disposed. The burner consists mainly of the spider 10, the body part 11, and the fuel supply conduit pipe 12. The body part 11 is provided with the jet opening 13 and the fuel overflowing chamber 14, the chamber being of proportionally larger bore than the jet opening so as to form the valve seat 15. The fuel supply pipe 12 is provided with the conduit 16 hav-

ing side openings 17 for discharging the fuel into the chamber 14. The end of the supply pipe is reduced in diameter as indicated at 18 so as to form the chamber 14 between the end 18 and the bore of the chamber 14. The termination of the supply pipe forms the valve 19 engaging with the valve seat 15. The threaded part 20 of the supply pipe engages turnably with a similar threaded part 65 within the end of the body part 11, so that a turning of the supply pipe may cause a disengaging of the valve 19 from the valve seat, or a closing of the jet opening or orifice 13. The cap 21 is provided to insure an air-tight connection between the supply pipe and the body 11, while the supply pipe is loosely turnable within the body part 11. For cleaning the orifice 13, the orifice cleaner 22 is shiftably mounted in the bore 23 in 75 the spider 10 having a suitable hook end 24 formed so as to pass into and through the orifice 13 when so shifted.

The rear-end plate 6 is provided with a boss 25 upon which the arm 26 is swingably 80 mounted for holding the end 27 of the supply pipe at about the same distance from the burner as the bent end of the supply pipe is made to come to cause a suitable heating of the fuel oil when passing through the 85 supply along the side of the burner before entering the burner. The set screw 28 is provided for setting the supply pipe at a different angle in relation to the burner when so desired or required, the position indicated at 29 being suitable for the case and the time when the burner is burning with full force causing the flame to discharge out of the burner from the whole sides of the burner between the indicating numerals 30 90 and 31, while the position indicated at 32 is more suitable in case and for the time when the burner is burning low so that a low flame is discharging near the top of the burner only, as will easily be understood. 95

Each of the several grate or body members is provided with a suitable number of recesses 33 forming the discharge openings for the gas out of the burner, by placing the smooth side of one grate or body member 105 against the recessed side of the next grate or body member as illustrated in Fig. 3. The lips 34 form the air and fuel mixing chamber 35 and the vaporizing chambers 36 when placing a number of the grate or body members together, as will be understood from the illustrations in Figs. 2 and 3. 110

To prevent the oxidizing of the surface of the burner, I prefer to provide the surface of the burner with suitable recesses 37 and insert a non-oxidizing burner plate 38, 5 made of suitable material as clay, glass, or other similar substances for this purpose while the rest of the burner may be of gray iron or other cheap and suitable material.

For starting this burner and heating the 10 supply pipe before the burner is burning, a trough 39 is provided below the supply pipe along the side of the burner, as illustrated in Fig. 1.

Having thus described my invention, I 15 claim:

1. In a burner of the class described a swingably mounted supply pipe having means for controlling the fuel supply by the swinging movement of the supply pipe 20 adapted for suitable retorting when the burner is burning with full force as well as when burning low.

2. In a burner of the class described a suitable number of body members having a 25 suitable number of recesses extending from the center toward the edges forming the gas discharging openings when the several body members are placed side by side, one side or edge of the body members having no recesses forming the closed base when the several body-members are placed side by side, the sides with the discharging openings when the several recessed body members are so placed side by side forming other recesses 30 along the whole sides, and a suitable number of non-oxidizing grate-members disposed in the last named recesses of the body members when held together forming the burning surface, all substantially as de- 35

40 scribed.

3. In a burner of the class described a suitable number of triangular body-members having a suitable number of recesses in one of the flat sides extending from the 45 center toward the edges forming the gas dis-

charging openings when the several body-members are placed side by side with their flat sides, one of the triangular sides having no recesses forming the closed base when the several members are so placed together 50 for a burner of suitable length.

4. In a burner of the class described a suitable number of grate members having a suitable number of gas discharging openings, and a supply pipe disposed so as to 55 pass the discharge openings in the grate members leading into the burner having a threaded end near the entrance in the burner engaging with the burner so as to close up the conduit through the supply pipe when 60 tightly screwed into the burner, the shutting off of the supply pipe being arranged so as to bring the supply pipe where it passes the gas discharge openings in the grate members more up to the upper discharge openings where the gas naturally will discharge 65 when the burner is burning low while the same part of the supply pipe will be farther down near the lower discharge openings when the burner is burning with full force 70 as the gas will then still pass around the supply pipe in such low position.

5. In a burner of the class described a suitable number of grate members having a suitable number of gas discharging openings, a fuel supply pipe swingably mounted along one side of the burner before the gas discharge openings and terminating with the orifice in the burner, and an orifice cleaner disposed near the orifice of the supply pipe having an end suitably formed so as to slip into and through the orifice in the supply pipe when so operated.

In testimony whereof I hereunto affix my signature in the presence of two witnesses. 85

HERMAN F. RICHTER.
